UNITED STATES PATENT OFFICE.

HENRY W. CORY, OF ST. PAUL, MINNESOTA.

CASE FOR LAW-BLANKS.

SPECIFICATION forming part of Letters Patent No. 360,999, dated April 12, 1887.

Application filed February 16, 1885. Serial No. 156,005. (No model.)

To all whom it may concern:

Be it known that I, HENRY W. CORY, of St. Paul, in the county of Ramsey and State of Minnesota, have invented certain new and 5 useful Improvements in Cases for Law-Blanks, of which the following is a specification.

This invention has reference to an improved case for holding law and other blanks, maps, plans, &c., in such a manner that any 10 desired blank can be quickly selected from the case.

The invention consists of a blank-case the 15 body of which is made open at the top and provided with converging front and rear walls, the front wall being provided with V-shaped openings near the bottom, and of a series of 20 interior card-boards arranged in the body of the case and connected at the lower ends by knotted strings, which are attached to the rear card-board, passed through openings near the lower end of the remaining card-boards, and retained by the openings of the 25 front wall of the case.

In the accompanying drawings, Figure 1 30 represents a perspective view of my improved blank-case, and Figs. 2 and 3 are respectively a vertical longitudinal and a vertical transverse section of the same.

Similar letters of reference indicate corresponding parts.

Referring to the drawings, A represents the 35 body of my improved case for law and other blank forms. The body A is supported on a suitable stand formed of cross-legs B B, which are attached to the body in any suitable manner.

The body A of the case is closed by a lid, C, that is hinged to the rear wall of the case, and retained by a cord or strap, a, in open position, as shown in Fig. 3.

The body A of the case is made with fixed 40 transverse side walls and converging front and rear walls, and provided at its interior with a series of indexed card-boards, D, which are provided with perforations or slits b b near their lower corners. Through the 45 perforations or slits b b are passed knotted strings d, which are attached to the rearmost card-board, D, while the knotted front ends are passed through the V-shaped recesses d' to the outside of the casing, as shown in Figs. 1 and 3.

The different blanks are arranged between

the indexed card-boards D, each set of blanks next to its corresponding card-board. The 55 blanks are retained in position in the case A by drawing the knotted strings tight and then wedging them into the lower narrower parts of the V-shaped holes d', which retain the strings d in position. When the blanks are 60 gradually used up, the card-boards are moved up close to each other by retightening the strings d, and fastening them again by allowing them to drop into the lower parts of the 65 V-shaped holes d'.

When it is desired to take any one of the 70 blanks from the case, the card-board indicating the desired blank is taken hold of and thrown, with all the card-boards in front of the same, forward toward the front wall, as shown in dotted lines in Fig. 3, while the 75 remaining card-boards and blanks remain in position parallel to the rear wall. Access is thereby given to the required set of blanks, so that one or more may be conveniently removed.

In this manner a cheap and convenient 80 blank-case for lawyers and others is obtained, in which the blanks can be conveniently stored and removed for use. In place of the 85 strings for connecting the card-boards, any other means by which the card-boards are connected to the lower part of the case may be used, so that they cannot be removed from the case, and can be moved up close to the 90 blanks.

Having thus described my invention, I claim 95 as new and desire to secure by Letters Patent—

The combination of a case being open at the top, and having converging front and rear 100 walls, the front wall being provided with V-shaped openings near the bottom, interior card-boards for separating the blanks, having perforations at the lower corners, and knotted strings passing through the perforations of the 105 card-boards, said cords being attached to the rear card-board and retained by the openings of the front wall of the case, substantially as set forth.

In testimony that I claim the foregoing as my 110 invention I have signed my name in presence of two subscribing witnesses.

HENRY W. CORY.
